[57] ABSTRACT

An apparatus for activating carbon or other comminuted material is described. The apparatus includes a plurality of baffles upon which the material to be activated impinges as it falls through the activating apparatus. The bottom surfaces of the baffles are spaced and configured to define passages for the activating gas. Accordingly, the flow of activating gas through the material is in the form of a plurality of congruent paths which appear as branches of the main gas flow. All the material is therefore exposed to gases having substantially equal activating capabilities and a uniform activation is achieved. The combustion gases, which are given off from the fuel used to heat the activator, are utilized as the activating gases and a venturi is used to supply the activating gases to the activating chamber of the apparatus.

APPARATUS FOR ACTIVATING COMMINUTED MATERIAL

BACKGROUND OF THE INVENTION

Nearly all processes for activating carbon can be classified into one of three main classifications. The first is activation by chemical means utilizing phosphoric acid, sulfuric acid, zinc chloride and similar agents. The chemical is usually a strong dehydrating agent, and is normally added to organic material such as wood, peat, etc., and the mixture is then carbonized. The second category is that of activation by the use of air in a temperature range of 450°-550° Centigrade. The third category is that of activating by use of steam, carbon dioxide or combustion gases in the temperature range of 800°-1,000° Centigrade. The instant invention falls in the third of these categories.

Various types of apparatus are presently available for activating charcoal and similar materials by use of steam, carbon dioxide or combustion gases. Ordinarily, in the existing types of apparatus, the material to be activated is placed in an activating chamber in a manner which causes the carbon or charcoal to form what appears to be a column. A source of activating gases, which usually is an outside source, is used to supply the activating gases which filter through the column of carbon and thereby cause activation of the charcoal. After passing through the carbon, the activating gases are expelled into an exhaust chamber or a device which neutralizes them to eliminate their toxic characteristics.

All of these systems have some utility and have met with limited commercial success. However, they have certain inherent disadvantages. Perhaps the most important disadvantage is the fact that the activating gases pass through the entire column, or a major portion thereof, of the material being activated. As a consequence, the temperature and activating capability of the gas as it enters the column of material are substantially greater than they are after the gas has passed partially through the material. Accordingly, the first material subjected to the gas is activated to a higher extent than the material which is located further downstream from the gas entrance. In some instances the initial material is completely disintegrated, or turned to ash, while that further along the flow of gas is only partially activated.

Another difficulty of the presently existing apparatus stems from the fact that the temperature control of the activating gases and the material being activated is extremely difficult because of the serial flow of gas through the material. Attempts to improve the control of the equipment have resulted in complex and complicated structures which are large in size and high in cost.

SUMMARY OF THE INVENTION

The instant invention overcomes these disadvantages in that the activating gases are provided in a steady stream which is injected into the activating apparatus in a single stream which is then divided into several short congruent, or parallel, streams. The apparatus includes an activating chamber having a longitudinal axis and a gas inlet passage which extends through the chamber parallel to the longitudinal axis. A source of activating gas supplies gas to one end of the gas inlet passage. A

plurality of baffles are disposed in the chamber and define surfaces which are disposed along said inlet passage angularly with respect to the axis of the chamber. The baffles are spaced apart to form branch passages for the activating gas, which branch passages communicate with the inlet passage. As the material to be activated passes through the chamber it is deflected by the baffles and thereby intermixes.

Activating gas passes along the inlet passage and a portion thereof is diverted into each of the branch passages by the baffles while the remaining gas continues through the inlet passage to the succeeding branch passages. The activating gas therefore passes through the material in the respective branch passages and thereby subjects the material to gases having substantially equal activating capability. A gas outlet communicates with the branch passages to exhaust the gas from the activating chamber.

The inventive structure results in more output per unit volume as a result of the material being kept under favorable activating conditions during most of the time that it is in the activator.

BRIEF DESCRIPTION OF THE DRAWINGS

FIG. 1 is a perspective view partly in section and with the heating chamber and material inlet removed, of an embodiment utilizing dihedral type baffles.

FIG. 2 is a vertical sectional view of the embodiment of FIG. 1, including a combustion chamber and a venturi.

FIG. 3 is a perspective view of a second preferred embodiment of the invention utilizing semi-pyramidal baffles.

FIG. 4 is a vertical sectional view of the embodiment of FIG. 3.

FIGS. 4a and 4b are respectively a top view and an end view of one of the baffles used in the embodiment of FIG. 3.

FIG. 5 is a top plan view of the embodiment of FIG. 3.

FIG. 6 is a perspective view, partly in section, of a third preferred embodiment of the instant invention.

FIG. 7 is a vertical sectional view of the embodiment of FIG. 6.

FIG. 8 is a sectional view of the embodiment of FIG. 6 taken perpendicular to FIG. 7.

FIG. 9 is a fragmentary sectional view of the embodiment of FIG. 6 showing the use of parallel material inlets and parallel exhaust outlets.

FIG. 10 is a schematic representation of a modified form of the embodiment of FIG. 6 useful in understanding the construction and operation thereof and showing an alternate venturi design and location and also an alternate type of gas distributor.

DETAILED DESCRIPTION OF THE INVENTION

In FIG. 2 the inventive charcoal activator 10 includes a gas inlet 11 and a material feed inlet 12. The material to be activated is fed into the activation chamber 13 through the material feed 12. The activating gases enter the activating chamber 13 through the gas inlet 11.

Extending across the entire width of the activation chamber 13 are a plurality of baffles 14, which are equally spaced along the longitudinal vertical axis of

the activation chamber. The cross-sectional appearance of the baffles 14 is that of an inverted V. A second series of similarly configured baffles 15 is interposed between baffles 14. The two series of baffles 14 and 15 are disposed at right angles with respect to one another. Accordingly, baffles 14 and 15 respectively extend completely along two transverse axes of the activation chamber 13. With the exception of the uppermost baffle, each of the baffles 14 and 15 is provided with an aperture 16 in the approximate center thereof. These apertures are dimensioned such that a portion of the gas is diverted along the bottom surface of the baffle and a portion passes directly through the aperture to the next baffle. The configuration of the apertures 16 can be triangular as shown, circular, or any other convenient configuration. Because baffles 14 and 15 are alternately disposed at right angles, material entering activation chamber 13 through inlet 12 contacts the top surfaces of the baffles in sequential order. The material therefore follows an irregular path through the chamber 13 as the direction of travel is changed each time contact is made with a different baffle. This results in a thorough and uniform mixing of the material which is to be activated.

Arranged around the four corners of the activation chamber 13 is a plurality of exhaust gas collecting ducts 17, as shown in FIGS. 1 and 2. Collecting ducts 17 communicate with activation chamber 13 by means of vents 32, which are the spaces existing between the individual plates of a plurality of louvers 18. The louvers 18 are arranged at approximately 45° angles across the four corners of the activation chamber and slope downwardly toward the longitudinal axis of the activator so that gases passing along the bottom surfaces of the baffles 14 and 15 ultimately pass into collection ducts 17 through the vents 32. The gases cannot pass directly to the vents 32 because of the location of the vents with respect to the baffles 14 and 15. The V shaped baffles 14 and 15 are butted against the side walls of the activation chamber 13. Accordingly the baffles fill up with the activating gases and then the gases seep around the edges of the baffles through the material to be activated into the vents 32. In this manner the gases flow through the activator in a plurality of branches from the main flow path. The main stream of gases will ultimately impinge upon the apertureless uppermost baffle and then seep around the bottom edges of the baffle and then be expelled through vents 32.

Each of the exhaust gas collecting ducts 17 communicates with a main exhaust duct 19 which serves as an input to the combustion chamber 20 through the venturi 22. Exhaust duct 19 can be blocked off from venturi 22 by means of damper 33. A gas vent 25 is provided for expelling the activating gases.

The exhaust gases from the activating chamber 13 are directed from the main duct 19 into the combustion chamber 20 by way of the venturi 22. Air is injected into the venturi through an inlet 24. Fuel gas necessary for initial start up of the chamber 20 can be injected into the venturi through the fuel inlet 23. The venturi is useful in mixing the air and the exhaust or fuel gas to insure complete burning. After mixing with air in the venturi 22, the exhaust or fuel gas is burned in the combustion chamber 20, which is filled with refractory

granules 21. A vent 26 is provided to exhaust the gases from the combustion chamber when necessary. The vent 26 is provided with a plug 27. The combustion gases are conducted by way of conduit 28 from the combustion chamber 20 to the gas inlet 11 and then into the activation chamber 13 where they serve as the activating gases. The flow of combustion gases from the combustion chamber 20 to the conduit 28 can be blocked off by means of damper 34.

Immediately upon entering the activating chamber 13 most of the activating gases impinge upon the deflector 29, and are then directed upwardly toward the baffles 14 and 15. A portion of the gases impinges upon the bottom of the first baffle 14 and therefore travels along the baffle and through the material to be activated until exhausted by collecting ducts 17 through vents 32.

Another portion of the gases passes upwardly through the combustion chamber by way of aperture 16. A portion of these gases impinges upon the second baffle which is the first baffle 15, and ultimately passes out through the vents 32. The upward motion and splitting effect of the activating gases continues through the chamber 13 until the last of the gases impinges upon the last baffle 15 which is closed. These gases are then directed downwardly around the baffle and out through the vents 32 into the collecting ducts 17. Because of the configuration of the baffles and the vents 32, the combustion gases travel a series of parallel, or congruent, branch passages which are substantially uniform in length. The material under activation is located in the branch passages and therefore the material being activated in each passage is subjected to gases which are substantially uniform in their activating capability. The activated product is therefore more uniform than in existing activating apparatus.

The activated material is discharged through a product discharge aperture 30. Discharge can be aided by use of a continuously running screw conveyor or a movable plate in well known manner. Steam, or some other purging gas can be applied to the activated product by means of inlet 31.

The type of discharge mechanism used is partially dependent upon the manner of operating the activating apparatus. A continuous activating method preferably is used. In this method material is continuously fed into inlet 12 and continuously removed from outlet 30. The material is then activated as it passes through the activation chamber. A continuously running screw could be used as the discharge mechanism for this type of operation.

In an alternate but less desirable mode of operation, which is a batch operation, the chamber may be filled with material and gases enter the chamber while the material is static. After a predetermined period of time the material is sufficiently activated and is removed from the chamber. A valve plate could be used as the discharge mechanism for this operation. In this embodiment and in all succeeding embodiments hereinafter described the collecting ducts or outlet passages may open at the lower end into the product discharge to prevent the passages from becoming filled by entrained material.

A second preferred embodiment of the invention, the activator 40, is shown in FIGS. 3-5. An understand-

ing of this embodiment is more readily obtained by first viewing FIGS. 4a and 4b which show the baffles 44. FIG. 4a shows the baffle 44 as it appears when viewed along a line which is perpendicular to the gas inlet 41 shown in FIG. 3. The upper surface 46, that is the surface upon which the material to be activated impinges, is triangularly shaped and extends from an apex 53 along the upper edge of the two side surfaces 47, which slope angularly away from the upper surface 46 to the corners 54. The side edges 49 of the surfaces 47 and the upper edge 48 of surface 46 lie in the same plane. A row of baffles 44 is made by connecting the sides 49 of several of the baffles, as seen in FIGS. 3 and 5. The baffles 44 therefore are semi-pyramidal in configuration.

FIG. 4b is a view taken along a line parallel to the plane defined by the edges 48 and 49 and viewed from the bottom of the baffles. The sloped side surfaces 47 form triangular surfaces which become narrower toward the upward edge 48. Consequently, material to be activated contacts the surfaces 46 and 47 and slides downwardly off of one baffle toward a lower baffle. Also the activating gases, as they are diverted from the mainstream, pass the under surfaces of the baffles and through the material being activated until the gases impinge upon the top of the next succeeding baffle from where they are directed upwardly into the exhaust passage 42.

As shown in FIGS. 3 and 4, the inventive activator 40 includes an activating gas inlet passage 41 and two parallel activating gas outlet passages 42. Arranged between the inlet passage 41 and the outlet passages 42 are two material feed passages 43, through which the material to be activated is introduced into the activator 40. The material inlet passages 43 are formed from a plurality of baffles 44 and they extend transversely across the entire width of the activator 40. The individual baffles 44 are connected to form rows and a row extends across the width of the activator 40. In the example illustrated in FIG. 3 a single row contains three baffles; this is a design choice as any number can be used. The rows of baffles 44 are arranged in four columns, two of which have their uppermost portions respectively contiguous with the gas outlet passages 42 and the other two of which have their uppermost portions respectively contiguous with the two sides of gas inlet passage 41. The horizontal rows of baffles 44 are arranged such that the baffles in one row are staggered relative to the corresponding baffles in the adjacent row as shown in FIG. 5. The rows of baffles within a column are equally spaced along the longitudinal axis of the activator 40. The material inlet passages 43 are each formed from two columns of baffle rows. The vertical spacing of the rows of baffles within the two columns is the same. However, the two vertical columns are arranged such that the baffles within one column are staggered relative to the baffles in the adjacent columns as best seen in FIG. 4. This results in a staggering of the baffles within the two columns, and results in the descending material being deflected in a zig-zag path between the baffles in the adjoining columns.

Thus, although each row of baffles contains the same number of baffles the arrangement of the baffles within facing rows is different. This is best understood by viewing FIGS. 4 and 5, and considering two rows 50

and 51 of baffles which form the top of the right hand material inlet passage 43. Row 50 contains three complete baffles 44 joined at seams 52. Because the baffles 44 are semi-pyramidal in configuration the bottom edge of each baffle includes an apex 53 in the center of the top surface 46, FIGS. 4a and 4b are helpful in visualizing this configuration.

The baffles within row 51 are arranged so that the apexes 53 of this row are directly opposite the seams 52 of row 50. This results in a space 54 (FIG. 5) between the two rows of baffles which extends across the width of the activator 40 and which is sawtooth in configuration. For this reason as the material to be activated enters the activating chamber formed by the baffles 44, the material is deflected from one baffle to the other in its downward journey through the activating chamber. This causes the material to move in a zig-zag fashion down through the activating chamber.

The above described arrangement of baffles also results in a series of congruent, or parallel, branch gas passages, indicated by the arrows 45 in FIG. 4, which communicate between the inlet passage 41 and the outlet passage 42. For this reason as the gases entering the inlet passage 41 pass downwardly through the main passage 41, portions of the gases are diverted transversely through the smaller branch passages 45 to the exhaust passage 42. The material within the branch passages 45 is activated at this time.

The passages 45 are identical in configuration and dimension because of the uniform spacing of the rows of baffles 44 along the longitudinal axis of the activating chamber 40, and because the individual baffles 44 are identical. For this reason the activating capability of the gases as they pass through the material to be activated is substantially uniform and the activation throughout the activating apparatus is uniform and consistent.

Although it is not shown in FIG. 4, a gas distribution plate can be inserted into the gas inlet passage 41 to cause more equal flow of activating gases into the branch passages 45. A detailed description of the distribution plates is given with respect to the embodiment shown in FIGS. 6 and 7 hereinafter.

It should also be noted that the embodiment shown in FIG. 4 includes four columns of baffles and two gas outlet passages 42. The invention works equally well with a single gas outlet passage and two columns of baffles. This can best be visualized by eliminating everything to the right of the gas passage 41 in the embodiment shown in FIG. 4 and placing a solid wall on the right side of such passage.

It should also be noted that the activator shown in FIGS. 3 to 5 includes a combustion chamber, a venturi and associated conduits in the manner shown with respect to the embodiment shown in FIGS. 1 and 2.

A third embodiment of the invention, which is preferred over the preceding embodiments, is shown in FIGS. 6 to 10.

The apparatus 60 includes material feed passage 61, which contains the material to be activated 62. The material feed passage 61 extends between the side walls 63 of the activating apparatus 60, as best seen in FIG. 8.

The activating gases enter into the top of a gas inlet passage 64. The activating gases are then passed as

shown by the arrows in FIG. 7 through a series of congruent branch gas passages 65 through the material feed passage 61, and are then exhausted by way of the exhaust passage 66. The material feed passage forms an activating chamber.

The congruent branch passages 65 are formed by two columns of baffles respectively identified as 67 and 68. The individual columns of baffles are arranged such that the vertical axis of each column is parallel to the longitudinal axis of the activating apparatus 60. The individual baffles within a column are equally spaced along the longitudinal axis of the activating chamber 61 and slope upwardly away from the longitudinal axis thereof. However, the two columns of baffles are separated by a space which defines the material feed passage 61 which is symmetrically disposed with respect to the longitudinal axis of the activating chamber 61.

A plurality of a first type of gas distribution plates 71 are arranged in the gas inlet and outlet passages 64 and 66. The purpose of these plates is to cause uniform distribution of the gases to the branch passages 65. The configuration of these distribution plates is best understood with reference to FIGS. 7 and 8 and will be described in detail hereinafter. A second type of gas distribution plate, which is preferred over the first type, will also be hereinafter described with reference to FIG. 10.

A product discharge mechanism 70 is disposed at the bottom of the activating chamber 61. This is effective to remove the activated material from an activating chamber and is similar to those described with respect to the embodiment of FIGS. 1 and 2.

Additional details of the baffles 67 and 68 can be seen by viewing FIG. 8. As seen in this figure, the baffles 67 slope in one direction, while the baffles 68 slope in the other direction. That is, baffles 68 slope upwardly away from the left wall 63 of the combustion chamber as shown in FIG. 8, while the baffles 67 slope downwardly from the left wall 63 of the combustion chamber. The individual baffles 67 and 68 within the two columns of baffles slope in two directions. All the baffles 67 and 68 slope downwardly away from the side wall 74, to which they are the most proximate, toward the center plane of the activation chamber.

The material to be activated is fed into the activation chamber 61 by use of two feed inlet conduits 72 and 73.

As the material is inserted into the conduits 72 and 73, it contacts the top surfaces of the baffles 67 and 68. Because of the slope of the baffles with respect to the side walls 63, of the chamber, the material slides downwardly along the baffles toward the side walls and simultaneously slides toward the center of the activation apparatus. This causes substantial intermixing of the material as it travels downwardly through the activating chamber 61. A uniform mixture of the substance to be activated is therefore realized throughout the entire activation apparatus.

As shown in FIG. 6, the gas distribution plates 71 are in the form of isosceles triangles having an altitude which greatly exceeds the width of the base. The apex of each triangle is shown as flattened; however, this is an optional feature.

The triangular shaped distribution plates 71 are equally spaced along the baffles 67 and 68, leaving triangular spaces between the plates. Accordingly, as the activating gases enter the gas conduit 64, they pass along the distribution plate 71 and through the spaces between the plates. The gas distribution plates 71 therefore cause the gases to be equally distributed across the baffles 67 and therefore a uniform flow of gas through the branch passages 65 occurs. This results in a substantially uniform activation of the material within the activation chamber 61.

The embodiment shown in FIGS. 6 to 8 contains only one material passage 61, and only one gas outlet 66 and gas inlet 64. The apparatus can be modified to include two material passages and two gas outlet passages 66 in a manner similar to the embodiment of FIG. 9 which illustrated an activator 60 utilizing two material passages. Two additional columns of baffles 67' and 68' which are identical to the first two columns, are added to the activator. One of the additional columns communicates with the gas inlet passage 64 and the other communicates with an additional gas outlet passage 66'. Gas distribution plates 71 are arranged along both sides of both material feed passages. As gas enters gas inlet passage 64 a portion branches off in both directions through the two material feed passages 61 and 61' formed by baffles 67-68 and 67'-68'. The diverted gases pass through the material 62 and exhaust through gas outlet passages 66 and 66'.

The operation of the inventive charcoal activator will now be described. Referring to the embodiment shown in FIG. 2, the activating chamber 13 is filled with feed material through the inlet 12. Inlet 12 and outlet 30 are then closed, as are also dampers 33 and 34. The plug 27 is removed from outlet 26. Steam or purge gas is introduced at 31 to keep a slight pressure on dampers 33 and 34 and thus to prevent seepage of combustible fuel gas into the activating chamber. An outside source of combustible gas is introduced slowly at 23 and ignited at outlet 26. Air is then added through air inlet 24 to cause combustion in the combustion chamber 20. The rate of temperature increase inside the combustion chamber 20 can easily be controlled by adjusting the air and fuel gas. When the temperature in the combustion chamber has reached the desired activating temperature, damper 34 and exhaust vent 25 are opened. The steam or purge gas is turned off at 31 and the plug 27 is inserted in vent 26 causing the combustion gases from combustion chamber 20 to pass through conduit 28 and inlet 11 into the activating chamber 13. The activating gases then pass through the material to be activated which is in the branch passages formed by baffles 14 and 15 and louvers 18, and out through exhaust vents 32 into the exhaust ducts 17 and thence through exhaust duct 19 to the exhaust vent 25. If desired, hot exhaust gases from exhaust vent can be used to preheat air coming in through 24. After the temperature in activating chamber 13 reaches the desired activating temperature the supply of fuel gas through 23 may be gradually diminished and damper 33 may be gradually opened to allow some of the gases leaving the activating chamber to be aspirated into the venturi tube and burned in the combustion chamber. These gases have been found to have sufficient heating value to sustain the desired temperature in the activator.

The embodiment shown in FIGS. 7 and 8 is designed to be started up with a portable combustion chamber which can be removed once the activating chamber is in operation. Initially, damper 82 is open and damper 83 is closed. Hot gases from the portable combustion chamber are introduced through inlet 84 and pass through the venturi 78 and the inlet passage 64 to the branch passages 65 which are formed by baffles 67 and 68. After passing through the material in the branch passages 65, the activating gases are transmitted by way of passages 66 and 79 to the exhaust outlet 75. When the temperature inside the activating chamber 61 reaches the desired activating temperature, damper 82 may be gradually closed and damper 83 may be gradually opened so that some of the exhaust gasses from the activating chamber are aspirated into venturi 78 by the flow of air through inlet 81 where they are burned. Alternately, steam at 150 to 200 pounds of pressure can be used to aspirate the combustible gases into the venturi. The volume of steam needed is considerably less than the volume of air. If steam is used, air must be added at the venturi discharge to burn the combustible gases. The resulting combustion gases pass into the activating chamber where they serve as activating gases. An alternate method of starting up the activator, which is somewhat faster and is therefore preferred, is to charge the activator with a portion of red hot charcoal. Unheated charcoal is then used to finish filling the activating chamber. Air is added gradually through venturi inlet 81 to prevent the temperature from rising too rapidly.

The feed material entering the activating chamber is deflected by the top of the baffles 67 and 68 and therefore follows a discontinuous zig-zag course through the activating chamber as it contacts the various baffles. This results in a uniform mixing of the material to be activated.

Shown in FIG. 10 is the preferred configuration for the gas distribution plates. A first distribution plate 76 is arranged with its upper end located approximately midway between the baffles 67 and the side walls 74. This distribution plate slopes inwardly away from side wall 74 so that at the approximate longitudinal center of the activating chamber 61, the plate is contiguous to the column of baffles 67. Another gas distribution plate 77 is arranged below the upper distribution plate 76 and the uppermost point of this plate is also located approximately mid-way between the baffles 67 and side wall 74. Plate 77 also slopes inwardly away from side wall 74 so that the bottom is contiguous to the lowest baffle 67. Both the plates 76 and 77 extend the entire distance between the side walls 63 of the activating apparatus. A small angularly arranged plate 78 extends across the top of the second distribution plate 77. This plate is used to prevent gas from entering behind the plate 77. Though not shown in the drawings, straightening vanes may be attached to the distributor plates to prevent the activating gases from being forced to one side due to the slope of the baffles.

The activating gases are injected into the top of the gas inlet 64 and because of the central location of plate 76 approximately half of the gases pass on each side of the plate. The gases which pass to the right, as illustrated in FIG. 8 of the distribution plate 76, pass through the upper half of the column of congruent branch passages 65 which contain the material being

activated and are then exhausted by way of the gas outlet 66.

The portion of the gases which enter behind, or to the left of the plate 76, pass downwardly along the plate 5 until they impinge upon the right surface of the second plate 77. These gases then pass through the lower half of the column of congruent branch passage 65 and also are exited by way of the outlet passage 66.

FIG. 10 also shows an alternate configuration for the 10 venturi 78' and the air inlet 81'. The venturi is located in passage 80' and the air inlet 81' protrudes through the side wall of passage 79'. A second air inlet 86 and a deflector 87 are provided to allow air to be added at the venturi discharge so that the percentage of oxygen in the activating gases can be set at any desired level. Also 15 shown in FIG. 10 and labeled with the numerals 91 through 94 are the approximate locations of four thermocouples used to measure the activator temperature during test runs to be hereinafter explained.

A working model of the inventive device as shown in 20 FIG. 10 was constructed and test runs utilizing granulated charcoal were conducted. Data from three of the test runs is summarized in the following table.

	Activator		
	Summary of Test Runs		
	Run 1	Run 2	Run 3
30			
Feed size mesh Tyler	2½ x 4	4 x 6	4 x 6
*Feed lbs/day	1050	675	1048
*Product lbs/day	657	349	666
*Percent yield	62.7	51.8	63.5
*Iodine value	80.6	82.5	72.6
35 O ₂ % in activating gases	7.0	7.4	7.3
CO ₂ % in activating gases	9.4	10.6	9.5

45 * Data based on 4% H₂O wet basis

** Average temperature in °F during test run

Although the yields from the test runs compare favorably with the yields obtained from a Herreshoff-50 type activator, even better yields could be expected if the percentage of oxygen in the activating gases were held below about 2 percent. The high oxygen content of the activating gases in the test runs was necessary to maintain a uniform temperature throughout the pilot activator, but uniform temperature could readily be 55 achieved by other conventional means such as better insulation.

It is now evident that the instant invention provides a 60 mechanism for uniformly activating a material, such as carbon or charcoal, by the provision of a plurality of identically configured and dimensioned congruent branch passages for the activating gas rather than a single series path as normally exists in the prior art apparatus. The unique structure by which the congruent branch passages are created therefore results in a more uniform activation than can be realized with the prior art devices.

There has been illustrated and described what is considered to be a preferred embodiment of the invention. It will be understood that various modifications may be made by persons skilled in the art without departing from the scope of the invention, which is defined by the appended claims.

I claim:

1. Apparatus for activating comminuted material comprising:

an activating chamber having a longitudinal axis and an inlet passage extending through said chamber in the direction of said axis,
 means for supplying activating gas to one end of said inlet passage;
 means for depositing comminuted material into said chamber;
 a plurality of baffles disposed in said chamber below said depositing means, said baffles defining surfaces which are disposed along said inlet passage angularly with respect to said axis and spaced apart to form branch passages for said activating gas having inlets communicating with said inlet passage, so that said material impinges upon said baffles during passage through said chamber and thereby intermixes and passes through said branch passages, and said gas passes along said inlet passage with a portion of said gas being diverted into each of said branch passages by said baffles and the remaining gas continuing through said inlet passage to the succeeding branch passage, said diverted gas passing through said material in said respective branch passages thereby subjecting said material to activating gases having substantially equal activating capability;
 and outlet means communicating with said branch passages for exhausting said gas from said activating chamber,
 said baffles including a first column of spaced parallel baffles sloping downwardly from a first side wall of said chamber to a second side wall of said chamber, and a second column of spaced parallel baffles sloping downwardly from said second side wall to said first side wall, said first and second columns of baffles being transversely spaced to

form a material passage between said columns, said baffles in both of said columns sloping downwardly toward said material passage.

2. The apparatus of claim 1 wherein said inlet passage lies on one side of said columns and extends completely between said first and second walls and completely along the longitudinal length of said chamber, and said outlet means lies on the other side of said columns and extends parallel to and coextensive with said inlet passage.

3. The apparatus of claim 2 further including a third column of baffles similar to said first column and a further column of baffles similar to said second column and spaced from said third column, said third and fourth columns being spaced from said first and second columns to define said inlet passage therebetween, and a second gas outlet means communicating with said fourth column identical to and spaced on the opposite side of said inlet passage from said first named outlet means.

4. The apparatus of claim 3 further including gas distribution means arranged in said inlet and said outlet passages to facilitate uniform supply of gas to said branch passages.

5. The apparatus of claim 2 wherein said inlet passage has gas distribution means contained therein, said gas distribution means comprising a first upper distribution plate with its upper end located approximately midway between the baffles and the side walls and its lower end located contiguous to the column of baffles at the approximate longitudinal center of the activating chamber and a second lower distribution plate arrangement below the upper distribution plate, the uppermost point of said upper distribution plate being located approximately midway between the baffles and the side wall and the bottom of said upper distribution plate contiguous to the lowest baffle.

6. The apparatus of claim 5 wherein said upper and lower distribution plates extend the entire distance between the side walls of the activating chamber and said lower distribution plate has means attached thereto to prevent gas from entering the space between said lower plate and the side wall.
